CLAIM

The ornamental design for a cosmetic container with magnetic closure, as shown and described.

DESCRIPTION

FIG. 1 is a front perspective view of a first embodiment of a cosmetic container with magnetic closure in a closed position showing our new design.

FIG. 2 is a front perspective view of the first embodiment of the cosmetic container with magnetic closure in an open position.

FIG. 3 is a front elevation view of the first embodiment of the cosmetic container with magnetic closure in the open position, of which the rear elevation, right side elevation, and left side elevation are mirror images thereto.

FIG. 4 is a top plan view of the first embodiment of the cosmetic container with magnetic closure.

FIG. 5 is a bottom plan view of the first embodiment of the cosmetic container with magnetic closure.

FIG. 6 is a front perspective view of a second embodiment of a cosmetic container with magnetic closure in a closed position.

FIG. 7 is a front perspective view of the second embodiment of the cosmetic container with magnetic closure in an open position.

FIG. 8 is a front elevation view of the second embodiment of the cosmetic container with magnetic closure in the open position, of which the rear elevation, right side elevation, and left side elevation are mirror images thereto.

FIG. 9 is a top plan view of the second embodiment of the cosmetic container with magnetic closure; and,

FIG. 10 is a bottom plan view of the second embodiment of the cosmetic container with magnetic closure.
